Office Action in counterpart Mexican Design Appl. MX/f/2019/001030, dated Mar. 5, 2021.

Primary Examiner — Keli L Hill(74) *Attorney, Agent, or Firm* — Blank Rome LLP(57) **CLAIM**

The ornamental design for a packaging container, as shown and described.

DESCRIPTION

FIG. 1 is a bottom plan view of a packaging container; FIG. 2 is a perspective view thereof;

FIG. 3 is a front elevational view thereof;

FIG. 4 is a left side elevational view thereof;

FIG. 5 is a back elevational view thereof;

FIG. 6 is a right side elevational view thereof; and,

FIG. 7 is a top plan view thereof.

The broken lines shown are included for the purposes of illustrating portions of the packaging container that form no part of the claimed design.
